SPIDER STRUCTURE

Douglas B. Walker, Portland, Oreg., assignor to Esco Corporation, a corporation of Oregon
Filed July 21, 1959, Ser. No. 828,615
3 Claims. (Cl. 263—47)

This invention relates to a spider structure, and, more particularly, to a spider structure employed for supporting coils, or the like, in an annealing furnace.

It is an object of this invention to provide a spider structure adapted to support materials in an annealing furnace which is characterized by superior resistance to the stresses imposed by materials loading and thermal conditions. Another object is to provide a spider structure of generally disc shape which is able to expand or contract during temperature changes at a nearly uniform rate between two circumferences. Other objects and advantages of this invention can be seen as this specification proceeds.

The invention will be explained in conjunction with an illustrative embodiment in the accompanying drawing, in which—

FIG. 1 is a fragmentary top plan view of a spider element embodying teachings of the invention and provided as a part of a base or separator plate assembly;

FIG. 2 is a diametric cross-sectional view of the spider seen in FIG. 1 and a cover plate; and

FIG. 3 is a view similar to FIG. 2 but shows the lowermost or base plate assembly and which rests on the floor of the furnace.

Referring now to FIG. 2, the numeral 10 designates generally a separator plate spider and the numeral 11 a cooperating separator cover plate therefor.

In the typical annealing furnace, a plurality of separator plate assemblies, including the cooperating elements 10 and 11, are assembled in vertically-stacked, spaced relation, the spacing being achieved through a riser stool generally designated by the numeral 12. Thus, the space between adjacent assemblies can accommodate a plurality of coils, or the like, for the annealing process.

The lowermost or base assembly is seen in FIG. 3 and is seen to include a base plate spider designated generally by the numeral 110 and a base cover plate designated generally by the numeral 111. In top plan, the spiders 10 and 110 have about the same configuration. The separator plate spider 10 is equipped with an axially-extending drilled hole 13 and the base plate spider 110 is equipped with a larger axial opening 113.

Each cover plate is essentially disc-shaped and is equipped with an outward taper, as can be readily appreciated from a consideration of the drawing. The cover plate 11 is equipped with opposed bosses 11a and 11b about the axis thereof, boss 11b being received within a recess 14 in the top surface of spider 10. The upper boss 11a may be received within the circular axial opening 12a of another riser stool (not shown).

Each cover plate 11 or 111, as the case may be, has the top and bottom walls thereof 15 and 16, and 115 and 116, respectively, angularly related to provide an outwardly converging taper in the portion of the plate adjacent the plate's periphery. The top surface of the spiders 10 and 110, these top surfaces being designated by the numerals 17 and 117, respectively, are equipped with an outwardly, upwardly inclined annular portion which mates with the bottom walls 16 and 116 to snugly bear against the same. Exemplary of the taper provided in cover plates 11 and 111, and therefore in the surfaces 17 and 117, is one inch in about sixteen and one-half inches of radial length. In this instance, the diameter of the cover plate 11 and 111 would be 46½", with the 16½" dimension being meas-

2

ured in from the periphery. Thus, there is provided a portion 18 and 118 in the two cover plates that is un-tapered. The taper referred to is provided in both top and bottom walls 15 and 16, or 115 and 116, as the case may be.

Referring now to FIG. 1, it will be noted that the spider 10 is equipped with a hub or central portion 19. When the spider 10 is installed in a separator plate assembly, it will be oriented generally horizontally. In such condition, the arms 20, which radiate outwardly from the spider hub 19, will be generally horizontal. The arms 20 are generally divergent, and can be characterized as having a compound radial contour in a plane perpendicular to the vertical center line of the spider. The compound curvature referred to can be best seen in FIG. 2, and with reference to the portion 20a of each arm, which portion is immediately adjacent the hub 19, or, in other words, the shank-end of each arm 20. The portion 20a is seen to be curved toward an adjacent arm—the adjacent arm being that to which the end of an arm is attached as at 20e.

The compound curvature is further provided by a portion 20b of each arm which is adjacent to the portion 20a but spaced from the hub 19. The portion 20b is seen to be curved away from the adjacent arm—the adjacent arm being that one to which the arm in question is attached at its end 20e.

Each arm 20 is provided with a portion 20c adjacent the portion 20b and on the side thereof remote from the hub 19, which is arcuately outwardly disposed. The portion 20c is seen to project radially outward a distance beyond the end portion 20e and, in effect, defines one of the circumferences referred to hereinbefore. The other circumference is defined by the hub 19.

Connecting the portion 20c of each arm with the portion 20e is an essentially straight portion 20d. The portion 20e can be seen to be inwardly arcuately formed.

The overall configuration of each arm is that generally of a hook or interrogation mark, whereby the end remote from the hub is closer to the hub than an intermediate portion—the intermediate portion being the portion designated 20c. Each arm is integrally connected at one end, the shank end, with the hub 19 and at its other end with an adjacent arm.

Each projecting portion 20c is equipped with an upwardly flange 21 which serves to confine the cover plate 15 against lateral movement. The spider 110 is equipped with corresponding flanges 121 providing the same operation relative to the cover plate 111.

Each spider is seen to have arms having a diminishing cross-section as one proceeds from the shank end outwardly. Specifically, the width of each arm 20 decreases in proceeding from the portion 20a through the portion 20d. A taper in the vertical direction is provided in each arm 20, as can be seen from a consideration of FIG. 2.

I have found that substantially all of the inherent differences in the magnitude of forces caused by thermal expansion and contraction are transposed to adjacent spider arms by reason of the contour or configuration of the arms. This results in changing the diameter of a circumference in the horizontal plane through any given point on a spider arm at any one temperature, and thus compensating for the difference in the magnitude of forces.

Example

A separator plate assembly including a spider 10 and a cover plate 11 was placed in continual service for a period of twelve months, with temperature changes from normal atmospheric temperatures up to about 2000-2200° F. Each cycle of operation included heating the assembly to the high temperature indicated and return to normal atmospheric temperature. The assembly seen in FIG. 2 has withstood this service condition through ap-

proximately seventy cycles without cracking or showing any other deleterious defects.

While, in the foregoing specification, I have set forth a detailed description of an embodiment of the invention for the purpose of explanation thereof, many changes in the details herein given will be appreciated by those skilled in the art without departing from the spirit and scope of the invention.

I claim:

1. A spider, comprising a unitary metal body having a central hub and a plurality of generally radially-extending, identical arms, each of said arms having a first end connected to said hub and a second end connected to an adjacent arm intermediate the ends of the adjacent arm, each of said arms having a portion intermediate its ends projecting radially outward a distance beyond the connection of said second end with said adjacent arm, each of said arms, in proceeding from said first end to said intermediate portion, diminishing in cross-sectional area and having first a portion concavely related to said adjacent arm, second a portion convexly related to said adjacent arm, third a portion concavely related to said adjacent arm and providing said intermediate portion, and fourth a portion interconnecting the third portion and said adjacent arm.

2. A spider, comprising a unitary metal body having a central hub and a plurality of generally radially-extending, identical arms, each of said arms having a first end connected to said hub and a second end connected to an adjacent arm intermediate the ends of the adjacent arm, each of said arms having a portion intermediate its ends projecting radially outward a distance beyond the connection of said second end with said adjacent arm, each of said arms, in proceeding from said first end to said intermediate portion, diminishing in cross-sectional area and having first a portion concavely related to said adjacent arm, second a portion convexly related to said adjacent arm, third a portion concavely related to said adjacent arm and providing said intermediate portion, and

fourth a portion interconnecting the third portion and said adjacent arm, the fourth portion including a straight part adjacent said third portion and an arcuate part adjacent said adjacent arm, said arcuate part being convexly related to said hub.

3. A spider, comprising a unitary metal body having a central hub and a plurality of generally radially-extending, identical arms, each of said arms having a first end connected to said hub and a second end connected to an adjacent arm intermediate the ends of the adjacent arm, each of said arms having a portion intermediate its ends projecting radially outward a distance beyond the connection of said second end with said adjacent arm, each of said arms having top and bottom walls and in proceeding from said first end to said intermediate portion diminishing in cross-sectional area and having first a portion concavely related to said adjacent arm, second a portion convexly related to said adjacent arm, third a portion concavely related to said adjacent arm and providing said intermediate portion, and fourth a portion interconnecting the third portion and said adjacent arm, said third portion being equipped with a flange upstanding from said top wall whereby said top wall is adapted to receive and support a cover plate.
